[57] CLAIM

The ornamental design for a toilet seat handle, as shown and described.

DESCRIPTION

FIG. 1 is a perspective view of a toilet seat handle showing my new design;

FIG. 2 is a rear elevational view thereof;

FIG. 3 is a top plan view thereof;

FIG. 4 is a right side elevational view thereof;

FIG. 5 is a left side elevational view thereof; and,

FIG. 6 is a bottom plan view thereof.

It is to be understood that FIGS. 4 and 5 are broken away for convenience of illustration.
